UNITED STATES PATENT OFFICE.

WILLIAM MONROE WHITE, OF MILWAUKEE, WISCONSIN.

HYDRAULIC TURBINE.

1,114,419.

Specification of Letters Patent. Patented Oct. 20, 1914.

Application filed December 24, 1913. Serial No. 808,910.

To all whom it may concern:

Be it known that I, WILLIAM MONROE WHITE, a citizen of the United States, residing at Milwaukee, in the county of Milwaukee and State of Wisconsin, have invented a certain new and useful Improvement in Hydraulic Turbines, of which the following is a specification.

This invention relates to improvements in the construction of hydraulic installations and is especially applicable to hydraulic turbine installations of the Francis, direct-connected, vertical shaft type.

An object of the invention is to provide a hydraulic installation which is simple in construction, efficient in operation, and which may be installed at minimum cost.

One of the more specific objects of the invention is to provide a simple and suitable support for the dynamo electric machine which is directly connected to and located above the hydraulic machine, without subjecting other turbine elements to endangering conditions such as excessive weights.

Another object of the invention is to provide suitable struts for directly supporting the dynamo electric machine of a hydraulic installation from the foundation, these struts being formed as guide vanes which offer the least obstruction to the fluid passing the struts while entering or leaving the hydraulic machine.

While the invention as disclosed is applied to an installation in which a direct connected Francis turbine and electric generator are embodied, it should be understood that the invention is equally applicable to centrifugal pump installations in which the driving motor is located above the pump and is direct connected thereto.

A clear conception of an embodiment of the invention may be had by referring to the drawing accompanying and forming a part of this specification, in which like reference characters designate the same or similar parts in the various views.

Figure 1 is a top view partly in section, of a Francis type hydraulic turbine installation. Fig. 2 is a transverse vertical section 50 through an installation of the type disclosed in Fig. 1, the section being taken along the line II—II of Fig. 1 looking in the direction of the arrows.

The Francis turbine runner 6 is direct 55 connected with the dynamo electric machine

or dynamo 9 by means of the vertical main shaft 7. The runner 6 is housed in a suitable turbine casing 15, which has the main shaft bearing 8 formed in one therewith, and which has its weight supported directly 60 upon the foundation through the foundation plate 14. The discharge end of the runner 6 connects with the discharge flume 12, which in turn connects with the usual tailrace not shown. The movable guide vanes 5 are mounted in suitable bearings formed in the stationary turbine casing 15 and are adapted to control the flow of water to the runner 6. The guide vanes 5 are operable by means of the usual guide vane actuating 65 mechanism 11. The stationary guide vanes 4 are formed in the speed ring which is secured to the casing 15 in the usual manner. The turbine inlet casing which is disclosed as a sheet metal spiral casing 1, forms a 70 pressure inlet chamber 13 which connects directly with the speed ring and turbine inlet opening. The guide vanes 4, 5, are so formed that they direct the water entering the runner 6 from the chamber 13, toward 75 the runner at the proper angle.

The dynamo electric machine or generator 9 is supported upon a suitable lower frame 10 provided with suitable supporting pads at its lower end. The struts 3 are arranged 80 in a circular series being formed as directing or guide vanes for the water passing through the turbine casing, and are provided at their upper and lower ends with suitable pads. The pads at the lower ends of the struts 3 85 coact directly with the foundation plate 14, while the pads at the upper ends of the struts coact directly with the pads at the lower end of the frame 10. It will thus be noted that the weight of the generator 9 is 90 carried directly by the foundation 2 through the struts 3 without subjecting other turbine elements to excessive weights. The formation of these struts 3 as directing or guide vanes furthermore assists in preliminarily 95 properly directing the water admitted to the turbine from within the chamber 13, while these struts produce but a very slight obstruction to the passing water.

During the normal operation of the turbine the water is admitted from the chamber 13 past the struts 3, stationary vanes 4, and movable guide vanes 5, and through the runner 6 to the discharge flume 12. The power generated by the turbine is controlled by 100 105 110

means of the usual guide vane actuating mechanism 11 which positions the movable guide vanes 5. While the invention as disclosed shows a sheet metal spiral casing 1, it should be understood that the provision of a direct support for the dynamo electric machine through the struts 3 may be applied to any other type of casing, such as cast iron, concrete or other forms generally used. It should also be noted that while the struts 3 are shown in the present disclosure as being entirely independent of the casing 1, these struts may be formed directly in one with and as a part of the casing 1.

15 It should be understood that it is not desired to be limited to the exact details of construction shown and described, for obvious modifications will occur to a person skilled in the art.

20 It is claimed and desired to secure by Letters Patent,—

1. In a hydraulic machine, a casing for conducting a fluent medium, a foundation supporting said casing, means carried by said foundation and extending through said casing, and a dynamo electric machine carried by said means.

2. In a hydraulic machine, a casing for conducting a fluent medium, a foundation supporting said casing, struts carried by said foundation and extending through said casing, and a dynamo electric machine located above said casing and supported by said struts.

3. In a hydraulic machine, a casing for conducting a fluent medium, a foundation supporting said casing, a runner within said casing, a dynamo electric machine connected to said runner and located above said casing, and means passing through said casing for

supporting said dynamo electric machine upon said foundation.

4. In a hydraulic machine, a casing, a foundation supporting said casing, a runner within said casing, means for directing fluent medium from the interior of said casing toward said runner, a dynamo electric machine connected to said runner and located above said casing, and means passing through said casing for supporting said dynamo electric machine upon said foundation, said supporting means being formed to direct fluent medium from within said casing toward said runner.

5. In a hydraulic machine, a casing, a foundation for supporting said casing, a runner within said casing, a dynamo electric machine direct connected to said runner and located above said casing, and means adapted to guide fluent medium from the interior of said casing toward said runner and supporting the weight of said dynamo electric machine upon said foundation, said means passing through said casing.

6. In a hydraulic machine, a sheet metal casing, a foundation supporting said casing, a turbine runner adapted to receive its actuating fluid from within said casing, a dynamo electric machine connected to said runner and located above said casing, and a guide vanes passing through said casing and supporting said dynamo electric machine upon said foundation.

In testimony whereof, the signature of the inventor is affixed hereto in the presence of two witnesses.

WILLIAM MONROE WHITE.
